UNITED STATES PATENT OFFICE

W. BARTLETT JONES, OF CHICAGO, ILLINOIS

SPONGE APPLICATOR

Application filed March 15, 1933. Serial No. 261,913.

The present invention relates to applicators for materials such as detergents and the like, and in particular to a combination scrubber and material reservoir. It has particular reference to a body brush or scrubber adapted to contain soap.

Although the article of the present invention is not limited to use with soap and other such detergents it is more particularly designed and adapted for such use.

One object of the invention is to provide a useful reservoir or container for materials having a utility comparable to soap.

Another object is to provide a porous envelope for soap and the like used in the form of powder, cake, chips, lumps, gel, etc.

Another object is the provision of a cellular envelope of water resistant material such for example as a rubber sponge, so that the material is immediately available from surfaces of the cells rather than from fibers, such as fabric.

A particular object is the provision of a refillable bath brush or sponge, or both, which has a pocket to contain soap.

Various other objects and advantages of the present invention will be apparent from the following description of the invention as exemplified in the embodiments illustrated in the accompanying drawing showing rubber sponge and soap as the preferred examples of materials. In the drawing,

Fig. 1 is a plan view of a rubber sponge containing a cake of soap.

Fig. 2 is a cross section of the sponge of Fig. 1 on the line 2-2.

Fig. 3 represents a plan view of a sponge made of two separate slabs of rubber.

Fig. 4 is a side view of the sponge of Fig. 3.

In the ordinary use of soap, it is rubbed directly on the skin, and strongly alkaline soaps injure delicate skins. By means of the present invention the soap itself may never make contact with the skin without dilution with water, which must first penetrate the casing or envelope and there dissolve the soap to carry it to the surface for use.

In using soap its slipperiness is frequently a considerable nuisance, making it difficult to pick up and to hold and use soap. The

present invention provides a friction means for overcoming all these difficulties.

Ordinary soap floating or resting in water is wasted by dissolution of it. The article of the present invention provides a storage structure about the soap from which dissolved soap is slowly diffused into the surrounding water, and in which it is held in available form when removed from water for using it. The present invention also provides a floating article which keeps the soap at the surface where it is visible and available.

Wet soap left in a dish or tray drips a strong soap solution into the tray, which is unsightly and wasteful. The present invention obviates the use of a tray and prevents such dripping. What liquid adheres to the soap or to the envelope is held therein against dripping and when the envelope dries out the soap residue is widely dispersed and available for immediate solution as a film coating at the walls of the cellular structure of the envelope. Non-absorbing material aids in making the dried detergent material immediately available on supplying water.

The soap containing article of the present invention is preferably flexible so that on squeezing it air in its pores is forced to the surface, forming a soap lather much more readily than can be produced by any ordinary use of soap. The invention in its preferred form provides an article of economy for the household in providing a receptacle or pocket for small pieces of soap that are not conveniently used in the ordinary way, and which are frequently broken up and wasted as solid lumps through the drain.

The article may be used in many places, for example in washing windows, dishes, or other places where a liquid and a cleaning agent and friction are desired. Materials such as an acid cake of fused sodium acid sulphate may be employed where an acid wash is required, as in cleaning marble, terra-cotta and the like.

In the drawing there are shown several practical structures embodying the invention. I have found that a variety of forms and modifications may be employed, but that

for the most universal use certain considerations are important. The form of Figs. 1 and 2 comprises a flat piece of sponge rubber which is doubtlessly the most practical and available material for the purpose. The body is indicated by the numeral 10. Inside the rubber a pocket 11 is formed by cutting it through from the exterior, thus forming an opening 12. The opening is made from 10 one end and along an edge, and it is practically concealed and is closed in the normal status of the article. The pocket 12 is reached through a narrow or constricted passageway 13 which may be stretched for 15 inserting into the pocket a cake of soap 14, larger than the normal area of the channel. The length and the narrowness of the channel prevent the cake slipping out through the opening, and aid in keeping the channel 20 closed by means of the normal resilience of the rubber.

The soap shown is large and it may be larger than the normal size of the pocket because of the ability of the envelope to 25 stretch. Eventually it will be smaller. When smaller the friction of the rubber on the soap is greater than when the rubber is stretched about the soap, and this compensates for the reduced size of the soap in the packet.

30 In Figs. 3 and 4 I show two layers of material, such as the rubber sponge slabs 21 and 22, secured together at the edges, as by thread 23 leaving an opening 24 for soap. By placing the threads at the edge of the 35 article a pocket 25 is formed which is substantially equal to the full area of the slabs. If desired a narrow constriction or channel 26 may be made by securing a limited area of the slabs to each other as indicated at 27.

40 I have found that the lathering qualities are improved by greater flexibility, attained by the use of a thin layer of sponge covering the soap. I have also found that the finer the cellular structure of the sponge the 45 thinner the layer should be to get satisfactory results. I have also found that looseness of the soap cake in the pocket is helpful. It is also desirable to use sufficient 50 thickness of material so that the soap is invisible through any of the pores of the sponge, and available only by a tortuous passage through the cellular structure.

It is to be understood that these conditions 55 are mentioned in reference to the preferred forms of the invention as applied to use with soap and with rubber sponge material. In other embodiments as well as in the foregoing embodiments and for special 60 uses with soap various modifications may be made without in any way departing from the spirit of the invention as expressed in the appended claims. Mechanical mountings for sponges adapted to contain soap and the 65 like are considered to be within the scope of

the invention as expressed in the appended claims.

I claim:

1. A detergent article comprising in combination, an envelope consisting of two layers of sponge material secured together at flat surfaces to form a pocket, and detergent material in said pocket. 70

2. A refillable detergent article comprising in combination two layers of material secured together at coincident surfaces to form a pocket between them and an opening for said pocket, one of said layers comprising a porous spongy soft and resilient substance. 75

3. A refillable detergent article comprising in combination two separate flat slabs of sponge rubber secured together at the periphery of the slabs to form a pocket between the slabs, the securing of the two slabs being incomplete about the edges to leave an 80 opening into the pocket of less width than the pocket. 85

4. A refillable detergent article comprising a sponge envelope having when empty a detergent receiving pocket the sides of 90 which are normally in contact to form a solid sponge, said pocket having a constricted opening to the exterior of the sponge. 95

5. A refillable detergent article comprising an envelope of sponge material having at the periphery a thickness of material not greater than the total thickness of material above and below the pocket area. 100

6. A refillable detergent article comprising a block of sponge rubber suitable in form for a bath sponge, said block being internally cut as by a knife slit to form a pocket, said cut extending to the exterior and being constructed to form a constricted neck-like entry 105 into said pocket. 110

7. A sponge applicator comprising a solid sponge structure having parallel surface areas and having a slit formed within it of substantial area providing a pocket parallel to said surfaces for receiving material, said slit extending in a constricted neck-like opening to the exterior of the applicator. 115

8. A sponge applicator comprising a solid sponge structure having parallel surface areas and having a slit formed within it of substantial area providing a pocket parallel to and substantially midway between said surfaces, said slit extending in a constricted neck-like opening to the exterior of the applicator. 120

9. A sponge applicator comprising in combination a solid sponge structure having an intermediate slit formed within it of substantial area providing a pocket, said slit extending in a constricted area to the surface 125 of the sponge. 130

In testimony whereof I have hereunto affixed my signature.

W. BARTLETT JONES.
